CLAIM

We claim the ornamental design for the fork mount, as shown and described.

DESCRIPTION

FIG. 1 is a top perspective view of a fork mount in accordance with our new design;

FIG. 2 is a front elevation view of the fork mount of FIG. 1; FIG. 3 is a rear elevation view of the fork mount of FIG. 1; FIG. 4 is a left-side elevation view of the fork mount of FIG. 1, the right-side elevation view being a mirror image thereof; FIG. 5 is a top plan view of the fork mount of FIG. 1; and, FIG. 6 is a bottom plan view of the fork mount of FIG. 1. The portions of the fork mount shown in broken lines in the figures depict unclaimed environmental subject matter, are for illustrative purposes only, and form no part of the claimed design. Similarly, unshaded portions that appear between broken lines or beyond boundary or break lines (if any) in the figures form no part of the claimed design.
